Letter Patent No. 13,444
Letter Patent, May 18, 1816

The Schedule referred to on these Letters Patent and making part of the same containing a description in the words of the said Patent, of his machine for spinning sheep's wool & Cotton.

The machine is attached to a frame composed of joints or posts constructed on the usual principles, there being necessarily six posts of the length of the frame depending on the number of spindles to be applied, which may be varied agreeable to the wishes of the manufacturer; the machine is so constructed as that spindles are applied and used on both sides of the frame. Two pairs of the posts are raised near to each other across one end of the frame & motion is given to the machine by a large wheel moving on a horizontal axis between these two pair of posts and near the top thereof and accelerating in a direction transverse to the frame. Around the before mentioned wheel plays a band which also passes round a conical wheel movably fixed by means of a screw on the axis of the main cylinder lying longitudinally near the bottom of the machine on frame. Around which cylinder we placed the band or bands which turn the spindles & flies similar to those used in other cotton machines. The conical wheel is used so that by moving the band to different parts thereof the motion of the spindles is increased or diminished as occasion may require, and the wheel is made to slide on the axis of the cylinder, so that it may be placed in a situation to prevent the main wheel casting its band. The main wheel may be turned by means of a crank or be applied to a water wheel as occasion may require. On the end of the axis to the main wheel is fixed a flywheel which goes in unison with another flywheel

wheel form on a horizontal shaft or axis so constructed as to be in a right perpendicular to the machine. On each end of the last-mentioned shaft or axis is fixed another cog wheel, each of which on each side of the machine meshes with another cog wheel near the upper end of a perpendicular shaft or axis. On this last-mentioned shaft or axis are fixed three other cog wheels of different sizes or diameters, each of which by gearing with other wheels on the end of each set of feeding rollers gives motion to each of three sets of feeding rollers. The rollers by being firmly fastened draw the roving from the roving spools which are purposefully placed on a platform on the top of the machine and conduct it to the flies, & thence to the spools.

Each thread passes through three pair of fluted rollers which by reason of the difference in size of the wheels on the perpendicular shaft have ^{different} the speed with which they revolve, thereby drawing out the warp. On the first-mentioned horizontal transverse shaft or axis is fixed an end up screw which meshes with a tooth wheel fixed on a perpendicular shaft extending near to the bottom of the machine or frame. On this last-mentioned shaft is fixed a heart the rotation of which, acting on an arm in which is inserted a friction pulley, raises and lowers by means of other arms, the platform on which stand the spools on the spindles thereby equally distributing the yarn on the spools.
